CLAIM

The ornamental design for a tire-shaped coozie, as shown and described.

DESCRIPTION

FIG. 1 is a front, top-side perspective view of an embodiment of the present invention;

FIG. 2 is a front, bottom side view of the embodiment of FIG. 1;

FIG. 3 is a side view of the embodiment of FIG. 1;

FIG. 4 is a top side view of the embodiment of FIG. 1; and,

FIG. 5 is a bottom-side view of the embodiment of FIG. 1. In the figures, features illustrated in broken line are not part of the claimed design.
